UNITED STATES PATENT OFFICE

HERBERT V. THADEN, OF MOUNT LEBANON, PENNSYLVANIA, ASSIGNOR, BY MESNE ASSIGNMENTS, TO GENERAL AVIATION CORPORATION, OF NEW YORK, N. Y., A CORPORATION OF DELAWARE

AEROPLANE STRUCTURE

Application filed January 19, 1931. Serial No. 509,695.

My invention relates to improvements in the structure of aeroplanes, and particularly of those whose wings are of monocoque type. It consists particularly in a wing structure having arranged within it a container for fuel, ordinarily gasolene. The spar or frame of an aeroplane wing of monocoque type consists of a shell supported upon a succession of transversely disposed bulkheads or brace members. In an application for Letters Patent of the United States filed December 11, 1929, Serial No. 413,255, I have described an aeroplane wing whose spar is of monocoque type, and consists of a shell of metal corrugated in the direction of the length of the spar and of a succession of bulkheads formed also of sheets of corrugated metal. It is in an aeroplane whose wing structure is that of the said application for Letters Patent that I have developed my present invention, and in such association I shall show and describe it.

In the accompanying drawings Fig. I is a view in transverse section through an aeroplane wing having a fuel container incorporated in its structure, in embodiment of my invention; Fig. II is a fragmentary view partly in plan, partly in horizontal section, of the same structure; the plane on which the view of Fig. I is taken is indicated by the line I—I in Fig. II; Fig. III is a view in perspective of a gasolene tank unit. Such a unit or a plurality of such units are, in the practice of the invention, built into the structure of the spar of the wing; Fig. IV is a fragmentary view to larger scale, showing in section (on the plane IV—IV of Fig. I) certain details of assembly; Figs. V and VI are views corresponding to Fig. IV, and illustrating modifications.

The gasolene tank unit 1 shown in perspective in Fig. III may be understood to be such in shape and size as to be introduced into and substantially to fill the space within the shell 2 and between two immediately successive bulkheads 3 of the wing spar. It is a simple tank, penetrated by tubes 4 which when the tank unit is assembled will be understood to extend longitudinally of the spar. These tubes are secured in fluid-tight union to the tank walls, in openings formed in the

walls to receive them, and when secured afford passageways through the fluid-tight tank for the securing bolts 5 (cf. Fig. IV).

The bulkheads of such a structure as this ordinarily succeed one another at intervals so small that the space within the shell and between two immediately successive bulkheads is not large enough to receive the full amount of fuel which the aeroplane requires. Accordingly I provide ordinarily a plurality of such tank units.

The tank unit or the tank units 1 are assembled with the adjacent bulkheads 3 and are secured by through-bolts 5, which extend through the tubes 4 and through orifices formed for them in the bulkheads, to constitute an assembled component of the completed structure. Such an assembled component, including two tank units and three bulkheads, is shown in Fig. II. In the assembly suitable cushioning members, such as sleeves 6 and rings 7 of rubber are included, to afford adequate security and to relieve strain when abrupt changes of speed occur. The sheets of metal of which the bulkheads 3 are composed may be reenforced with plates 30 at the places where they are orificed for the passage of bolts 5.

It is essential in such a monocoque spar as this that the box structure, consisting of the shell 2 of corrugated metal, and the webs 20 of sheet metal to which at their forward and rear edges the sheets of corrugated metal are united, be permanently riveted, and this box structure constitutes a second preformed and unitary component of the completed structure. These two preformed components then are brought together by the insertion of the tank assembly through the open end of the shell assembly and when the two components are so brought to place the bulkheads are at their edges united by bolting or by equivalent union to the shell 2 and to the webs 20. In the spar structure so completed the bulkheads serve the double purpose of supporting and bracing the shell and of carrying the fuel tank.

In bringing together the tank assembly with the shell assembly and in securing the two together the filler necks 8 for the tank

units and the supply-line fittings 9 are carried through openings formed for them in the shell, and when the union has in other respects been made secure these parts also are made 5 fast.

Referring to Figs. V and VI, certain modifications appear, and in view of them the invention in broader aspect will be recognized. As shown in Fig. V, two adjacent bulkheads 10 3 may themselves be so incorporated in the tank structure as to become the end walls of the tank. The tank in this case is completed by a side-wall shell 11 which at its edges is secured in fuel-tight union upon the bulk- 15 heads.

Again, in Fig. VI a bulkhead is shown to consist of a partition wall 12 arranged within the tank and an auxiliary strip 13 secured to the tank externally and in the plane 20 of the extent of partition 12, to which external strip union of the shell 2 may be effected.

The fuel tank built and supported as described may be arranged at any desired place 25 in the extent of the spar, in the inboard or in the outboard portion, or in both.

I claim as my invention:

1. In an airplane wing having spaced, longitudinally-extending, reinforcing members, transversely-arranged interconnecting, vertical corrugated members connected at their ends to the wing brace members, said corrugated members being arranged at spaced intervals, tank means interposed between 30 said corrugated means and supported thereby.

2. In an airplane wing having spaced, longitudinally-extending, reinforcing members, transversely-arranged, interconnecting, 40 corrugated members connected at their ends to the wing brace members, said corrugated members being arranged at spaced intervals, tank means interposed between said corrugated means and supported thereby, said 45 tank means comprising a tank enclosure having open-ended pipes extending from side to side, therethrough, for receiving said tank supporting means.

3. In an airplane wing having spaced, 50 longitudinally-extending, reinforcing members, transversely-arranged, interconnecting, corrugated members connected at their ends to the wing brace members, said corrugated members being arranged at spaced intervals, 55 tank means interposed between said corrugated means and supported thereby, said tank means comprising a tank enclosure having open-ended pipes extending from side to side therethrough for receiving said tank supporting means, and yielding members between 60 said tank supporting means and the corrugated means and said tank.

4. In an airplane wing, longitudinally- 65 spaced, reinforcing members, transversely- arranged, interconnecting, spaced corrugated members, rods passing through said corrugated members and secured thereto, and a tank mounted on said rods whereby said tank is yieldingly supported by said corrugated members.

5. In an airplane wing, longitudinally-spaced, reinforcing members, transversely-arranged, interconnecting, spaced, corrugated members, rods passing through said corrugated members and secured thereto, and a tank mounted on said rods whereby said tank is yieldingly supported by said corrugated members, and attaching plates reinforcing said rods at the point of attachment 70 to said corrugated members.

6. In combination in an airplane wing having longitudinally-arranged, spaced, reinforcing members, a cover therefor comprising a corrugated skin with the corrugations arranged longitudinally of the wing, interiorly-arranged, spaced, corrugated members forming bulkheads between the longitudinal 75 reinforcing members, and means of supporting a tank by and between said interiorly-disposed corrugated supporting members.

In testimony whereof I have hereunto set my hand.

HERBERT V. THADEN.
